DISPENSING DEVICE.

Application filed September 20, 1926. Serial No. 136,450.

This invention relates generally to devices for dispensing measured quantities of material such as coffee.

It is an object of this invention to generally improve and simplify the construction of dispensing devices whereby they may be cheaply manufactured in large quantities.

It is a further object of this invention to devise a dispensing device which will incorporate a novel measuring means which may be constructed entirely of sheet metal.

It is another object of this invention to devise a dispensing device provided with a novel form of support bracket whereby it may be readily detached for refilling.

Further objects of this invention will appear from the following description in which we have set forth the preferred embodiment of our invention. It is to be understood that the invention as defined by the appended claims is to be accorded a range of mechanical equivalents consistent with the prior art.

Referring to the drawings:

Figure 1 is a cross sectional elevational view of a dispensing device incorporating the features of this invention.

Fig. 2 is a cross sectional view taken along the line 2—2 of Fig. 1.

Fig. 3 is a cross sectional view taken along the line 3—3 of Fig. 1.

Fig. 4 is a detail view showing the means for attaching the closure to the receptacle.

Fig. 5 is a fragmentary detail showing the method of mounting the agitator.

The invention comprises generally an inverted receptacle or jar having a cup-shaped closure detachably secured to the lower open end of the same, the closure carrying means whereby measured quantities of material may be discharged. Thus referring to the drawings there is shown a receptacle 10 preferably in the form of an inverted glass jar, to the lower open end of which is secured the closure member 11. This closure is preferably in the form of a cup constructed of pressed sheet metal and is provided with an upper rim 12 which is adapted to be detachably secured to the rim 13 of the jar 10. The particular form of detachable connection shown comprises a plurality of projections 14 upon the outer periphery of the rim 13, these projections being preferably molded integral with the jar and being adapted to engage L-shaped slots in the rim 12. The re-

silient metal tongues 16 formed by the slots 15 are also notched as at 17 whereby when the rim is positioned upon the jar and rotated, the extensions 16 clip over the projections 14. Preferably the projections 14 are spaced unevenly about the periphery of the rim 13 so that the closure can be only attached in one position with respect to the jar.

Mounted within the closure 11 and in spaced parallel relationship with the bottom wall 19 thereof, there is a metal disc 20, the periphery of which is seated upon a shoulder 21 extending about the sides of the closure. Additional means for retaining this disc in position upon the shoulder 21 has been shown in the form of tabs 22 formed integral with the rim 12 and bent inwardly over the upper surface of the disc. The disc 20, together with the bottom wall 19, form spaced inner and outer walls enclosing a chamber 23 within which is disposed the measuring means. This measuring means comprises a rotatable metal disc 24 of slightly smaller diameter than the stationary disc 20. For centering and retaining the disc 24 in close contact with the lower surface of the disc 20 its edges are slidably seated upon a peripheral shoulder 26 provided as an integral part of the closure member 11 adjacent the peripheral shoulder 21. The edges of the disc 24 are also provided with a plurality of integral depending flanges 27 for engaging the inner surface of the closure 11.

The rotary disc 24 is provided with an aperture 29 offset from the center of the same. Secured to the underside of disc 24 adjacent the edges of this aperture is a metal band 30 having an outwardly flanged upper edge 31 which is secured to the disc 24 as by spot welding, and a lower inwardly flanged edge 32. This band forms a pocket 33 rotatable with the disc 24 for removing a measured quantity of material from the receptacle. For rotating the disc 24 there is provided a lever 34 preferably formed integral with the disc and projecting through an arcuate slot 35 provided in the side of the closure 11. By means of this lever the disc 24 and pocket 33 are adapted to be rotated through an angle of say 180 degrees with respect to the closure. The inner wall or stationary disc 20 is provided with an aperture 36 with which the pocket 33 is adapted to register in order to receive ma-

terial from the interior of the receptacle. The bottom wall 19 is likewise provided with an aperture 37 with which the lower end of the pocket 33 is adapted to register 5 when the disc 24 is rotated through an angle of say 180 degrees by means of the lever 34. Thus in one position of the disc 24 the pocket 33 will receive a measured quantity 10 of material from the receptacle and when the disc is rotated to bring the pocket into register with aperture 37 this measured quantity 15 of material will be discharged and aperture 36 will be closed by disc 24. Normally the disc 20 and bottom wall 19 are sufficiently close together to form a close sliding fit 20 with the upper surface of disc 24 and the flanged edge 32 whereby the material being dispensed will not tend to escape into the chamber 23, or will not jam between the stationary disc 20 and the rotatable disc 24.

When the material being dispensed tends to pack within the receptacle it is necessary to employ some sort of agitator movable upon movement of the lever 34. In this instance 25 there is provided an agitator in the form of a wire 39 having its upper end extending into the interior of the receptacle and having its lower end extending through central apertures 40 and 41 provided in discs 20 30 and 24 respectively. This lower end is then provided with an angular bend as at 42 and is extended through an aperture provided in the metal band 30, the inner terminal of the wire being bent over as at 35 43. With such an arrangement the agitator is securely mounted to the rotatable disc without the necessity of employing a soldered or welded connection.

In order to detachably mount the receptacle 10 to a suitable support there is provided 40 a resilient metal band 46 which is adapted to encompass the periphery of the jar, the intermediate portion of this band being flattened as at 47 whereby it may be 45 attached by screws to a suitable support. The free ends 48 of this band are preferably bent to form grooves 49 which serve to receive integral ribs or projections 50 provided upon the surface of the receptacle, thus 50 preventing rotation of the receptacle with respect to the band. To prevent longitudinal displacement of the receptacle with respect to the band there is provided a pair of

spaced circumferential ribs 51 between which the band 46 is adapted to be disposed. Other ribs 52 may be provided upon the rear side of the jar to engage the bent portions 53 of the band, thus supplementing the effect of ribs 51. In order to detach the receptacle from the band it is only necessary to 55 spring apart the band 46 and then slide the jar up or down.

It will be evident that a device of this kind may be cheaply manufactured since all 60 of the parts, with the exception of the receptacle and agitator, are constructed of sheet metal. Refilling is readily accomplished by removing the jar from the bracket and detaching the closure 11.

We claim:

1. In a dispensing device, a receptacle having an open lower end, a closure adapted to be detachably secured to said lower end, said closure having a chamber defined by spaced inner and outer walls, a rotatable disc of sheet metal mounted within said chamber, said disc being apertured, and a metal band secured to said disc adjacent the edges of said aperture thereby forming a pocket rotatable with said disc, said inner wall being apertured to permit flow of material from the receptacle into the pocket, and the outer wall being apertured to permit discharge of material from the pocket when said disc is rotated.

2. In a dispensing device, a receptacle having an open end, a closure adapted to be secured to said lower end, said closure having a chamber defined by spaced inner and outer walls, a rotatable disc mounted within said chamber, said disc being apertured, a metal band secured to said disc adjacent the edges of the aperture thereby forming a pocket rotatable with the disc, said inner and outer walls being apertured to permit discharge of material from the receptacle upon rotation of the rotatable disc, said inner wall and disc being apertured centrally, and an agitator having its upper end extending into the receptacle and its lower end extending through said central apertures and secured to said band.

In testimony whereof we have hereunto set our hands.

GEORGE F. WELLS.
RAYMOND R. MORGAN.
